CLAIM

The ornamental design for an orthopedic plate, as shown and described.

DESCRIPTION

FIG. 1 is a front elevation of an orthopedic plate showing our new design;

FIG. 2 is a top plan view thereof;

FIG. 3 is a bottom plan thereof;

FIG. 4 is a left end elevation thereof;

FIG. 5 is a right end elevation thereof;

FIG. 6 is a rear elevation thereof;

FIG. 7 is a front elevation of a modified embodiment of the design shown in FIGS. 1 through 6;

FIG. 8 is a top plan view thereof;

FIG. 9 is a bottom plan view thereof;

FIG. 10 is a left end elevation thereof;

FIG. 11 is a right end elevation thereof;

FIG. 12 is a rear elevation thereof;

FIG. 13 is a front elevation of a second modified embodiment of the design shown in FIGS. 1 through 6;

FIG. 14 is a top plan view thereof;

FIG. 15 is a bottom plan thereof;

FIG. 16 is a left end elevation thereof;

FIG. 17 is a right end elevation thereof;

FIG. 18 is a rear elevation thereof;

FIG. 19 is a front elevation of a third modified embodiment of the design shown in FIGS. 1 through 6;

FIG. 20 is a top plan view thereof;

FIG. 21 is a bottom plan view thereof;

FIG. 22 is a left end elevation thereof;

FIG. 23 is a right end elevation thereof; and,

FIG. 24 is a rear elevation thereof.
